(No Model.)

J. KURTZ.

FARM GATE.

No. 249,776.

Patented Nov. 22, 1881.

UNITED STATES PATENT OFFICE.

JACOB KURTZ, OF GREENCASTLE, PENNSYLVANIA.

FARM-GATE.

SPECIFICATION forming part of Letters Patent No. 249,776, dated November 22, 1881.

Application filed September 16, 1881. (No model.)

To all whom it may concern:

Be it known that I, JACOB KURTZ, a citizen of the United States of America, residing at Greencastle, in the county of Franklin and State of Pennsylvania, have invented certain new and useful Improvements in Farm-Gates; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has relation to improvements in farm-gates; and it consists in the construction and novel arrangement of the same whereby said gate may be opened and closed without alighting from a vehicle or horseback, all of which will be hereinafter more fully explained.

The annexed drawings, to which reference is made, fully illustrates my invention, in which—

Figure 1 represents a side view, part section, of my invention. Fig. 2 represents a vertical cross-sectional view of my improved gate. Fig. 3 represents a detail view of the sliding bar attached to part of the gate. Figs. 4, 5, and 6 represent detail views.

The letter A designates the gate, composed of the panels *a*, having their front ends secured between the vertical strips *a'*, and braced by an inclined bar, *a*², that extends from the upper end of said strips to the lower end of the rear post, B, which latter also secure the opposite ends of said panels. Said post B is provided at its upper end with a pin, *b*, that engages with and projects through a staple, *b'*, secured to a vertically-pivoted bar, *b*², attached to a fixed post, C, in the rear of the gate-post B. The latter post is further provided with a pin, *b*³, on the under side thereof, that engages a slotted plate, *b*⁴, secured to the cross-piece *b*⁵, and the gate is also provided at this end with a guard, *c*, that is securely fixed thereto.

D designates a bar in rear of the gate and secured to the lower end of the post C, upon which is placed a sliding bar, *c'*, that is provided with a notch, *c*², on one side thereof and about the center. Said bar *c'* has secured thereto one end of a cord or chain, *e*, on either side

of the gate, while the other end of said cord or chain passes around the rear of the gate-post B, and is secured thereto. On the rear and at the lower end of said post is secured a metal strap, *g'*, over which said cords or chains work in operating said gate.

Pivoted to the post C is the vertical bar *b*², above mentioned, the lower end of which has a projection, *c*³, which engages with the slot *c*² on the sliding bar *c'*. Said vertical bar *b*² has at its upper end a projection, *d*, and pin *d*¹, to which a chain, *d*², is attached, one end of which is attached to the pin *d*¹, and the other end is fastened to the upper part of a locking-latch, *d*³, that is pivoted near its center to and between the front vertical strips of the gate. Said latch, when the gate is closed, engages a notch, *d*⁴, in a cross-piece, *d*⁵, secured to the latch-post E, thereby locking the gate. The cross-piece *d*⁵ extends on either side of the latch-post, and is beveled, as shown, and the latch is provided with a guide-pin, *e*⁴, at its lower end to prevent said latch from sidewise movement.

To the ends *e*¹ *e*² of the sliding bar *c'* is secured a cord or chain, *e*² *e*³, which passes through staples *e*³ *e*³ on the posts F, and upwardly to the short end of an operating hand-lever, *f*, that is pivoted at *f*¹ to the top of the posts F. Said staples may be provided with suitable pulleys or rollers under which said chains may pass.

It will be seen by referring to the drawings that in constructing the gate each panel is somewhat shorter than the other from bottom to top. By this construction the upper portion of the post inclines forwardly, thus allowing the gate, when operated, to rise from engagement with the latch-post.

Having thus given a description of the different parts of which my improved farm-gate is composed, I will now proceed and explain the manner in which it is operated.

In operating the gate to open the same the hand-lever is pressed downwardly, and being pivoted to the post F will draw the cord or chain *e*² and throw the sliding bar *c'* to one side, at the same time carrying therewith the lower end of the pivoted bar *b*², and also the chain *d*², which movement causes the front end of the gate to be raised from engagement with

the latch-post, and allows the gate to be swung open by the said chain e^2 , and the pin b^3 in the bottom of the post B working in the slot in the plate b^4 aforesaid. When it is desired to close the gate the opposite hand-lever is worked in a similar manner after passing through the gateway, and a reverse movement of the parts b^2 c' e^2 closes and latches the gate.

It will be further seen that the peculiar construction of the slot in the plate b^4 , being of V shape, admits of the pin b^3 passing from one position to another, thereby causing the gate to swing, when operated, open.

A cord or chain, g , may operate the latch d^3 by being connected to the same and the vertical bar, b^2 , as shown.

Having described my invention, what I claim as new, and desire to secure by Letters Patent, is—

20 1. In a farm-gate, the same constructed as

described, the pin b and pin b^3 secured to the post B, the former working in the staple b' and the latter in the slotted plate b^4 , in combination with the sliding bar c' , having the slot c^2 , chains or cords e^2 e^2 e e , and the pivoted bar b^2 , 25 having the staple b' , projection c^3 , and chain d^2 , as shown.

2. The combination of the gate A, slotted plate b^4 , sliding bar c' , pivoted bar b^2 , and hand-levers operating said bar c' with the chain d^2 , 30 operating the latch d^3 , and the cords or chains d^2 e^2 e^2 e e operating the several parts, as shown, described, and for the purpose set forth.

In testimony whereof I affix my signature in presence of two witnesses.

JACOB KURTZ.

Witnesses:

JOHN STONER,
FRANCIS HOFFMAN.
